VENDING MACHINE

Benjamin W. Fry, University City, Mo., assignor
to National Vendors, Inc., St. Louis, Mo., a cor-
poration of Missouri

Application March 27, 1940, Serial No. 326,123

14 Claims. (Cl. 312—63)

This invention relates to vending machines, and with regard to certain more specific features, to improvements upon the construction shown in my United States patent application Serial No. 295,005, filed September 15, 1939, for Vending machine.

Among the several objects of the invention may be noted the provision of a vending machine which provides for selectivity of operation from various magazines loaded with articles such as books or the like, including simplified interlock means for preventing more than one operation at a time; the provision of apparatus of the class described which is simpler and more compact than former apparatus, including that of said former application, compactness being attained in part by an ejection by article reciprocation instead of one-way article movement; the provision of apparatus of the class described in which a purchaser may obtain the return of a coin after an unsuccessful attempt to obtain an item from an empty magazine or upon a change of mind under certain circumstances; the provision of apparatus of this class in which the full or empty condition of a magazine is made evident in a simple manner; and the provision of such apparatus which is provided with means for preventing damage in case of an attempted enforced operation under improper conditions, such as, for example, when an improper coin has been admitted to the machine. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation, reduced in scale;

Fig. 2 is an enlarged front elevation of the upper parts of Fig. 1, the front of the casing being removed;

Fig. 3 is a plan view of Fig. 1 with the casing removed;

Fig. 4 is a vertical section taken on line 4—4 of Fig. 1, certain upper parts being broken away for clarity;

Fig. 5 is a fragmentary view similar to the lower portion of Fig. 4, showing an alternative position of certain coin-released parts;

Fig. 6 is a vertical section taken on line 6—6 of Fig. 1;

Fig. 7 is an enlarged, detailed front elevation of a single magazine and dispensing means in cooperating position;

Fig. 8 is an enlarged horizontal section taken on line 8—8 of Fig. 4 but showing a coin inserted;

Fig. 9 is a vertical section taken on line 9—9 of Fig. 7;

Fig. 10 is a view similar to Fig. 9 (somewhat extended) showing the start of a forward part of a delivery operation;

Fig. 11 is a view similar to Fig. 10 showing the beginning of the rearward part of the delivery operation;

Fig. 12 is a view similar to Fig. 11 showing an attempted (but blocked) delivery operation from an empty magazine;

Fig. 13 is a vertical section taken on line 13—13 of Fig. 10; and,

Fig. 14 is a substantially horizontal section taken on line 14—14 of Fig. 10.

Similar reference characters indicate corresponding parts throughout the several views of the drawings.

Referring now more particularly to Fig. 1, there is shown at numeral 1 an enclosing casing, in the front 3 of which are tiers A, B and C of display panels 5, indicating what is carried in magazines 31 behind the respective panels. The term "magazine" herein means a supply compartment for articles to be vended, such as booklets. For example, the panels 5 may be opaque with suitable display characters (as shown), or, if desired, transparent, so that the articles in the magazines 31 may be seen. In the present example, booklets are the articles being vended, but the invention is applicable to the dispensing of other articles.

Below each tier of four panels 5 and in the casing 1 is a horizontal transit slot 7 from which branch four, downwardly directed selector slots 9. One transit slot 7 and four, branched selector slots 9 are beneath each tier of panels 5.

Between the respective slots 7 and the panels 5 and over the respective selector slots 9 are openings 11 behind which operate "full-empty" indicators 13, best shown in Figs. 7 and 9—12.

At the lower end of the casing 1 is an article delivery outlet 15. On the right-hand side is an upwardly-located coin-receiving slot 17. At 19 is a slot for a coin-return lever 21 which, when operated in the manner to be described, returns a coin through a passage 23 into the outlet 15 at 25.

Inside of the casing 1 are vertical side supports 27 which are rigidly spaced by means of three rigid shelves 29. Each shelf 29 is located beneath the front of a tier of four magazines 31 (Figs. 2-4 and 9-12).

Each magazine 31 consists of a pair of front corner angle pieces 33 which are held in a sloping position on a cross bar 35, the latter being supported rigidly upon the side plates 27. The rear of each magazine consists of back plates 37 turned up to form corners 39, the respective back plates 37 being fastened upon supports 41. The supports 41 are also rigidly carried between the side plates 27. Thus, the side plates 27 are rigidly spaced by, and with the shelves 29 and cross members 35 and 41 form, a rigid structural skeleton in which the tiers of magazines 31 are rigidly supported. The operating parts to be described are movably supported upon this skeleton.

Incidentally, the supports 41 behind the two lowermost tiers of magazines 31 support at their sides deflectors 43 for guiding rearwardly ejected booklets between the back 45 of casing 1 and the deflectors 43, so that said booklets are properly sent down to a lowermost guide chute 47 which directs them out to the openings 15. This refers to the booklets from the uppermost tiers, indicated at A and B. Booklets from the lower tier C do not pass behind any deflectors such as 43, but in front of a deflector 49 to the same outlet 15, as will be shown. In short the deflectors 43 cause the booklets to by-pass otherwise obstructing mechanisms, while no such mechanisms are beneath tier C.

Beneath each shelf 29 is a square (polygonal) shaft 51 which has lateral bearings 53 in the side plates 27 (see for example Fig. 7). The shafts 51 are rotary in their bearings. Inasmuch as all of them, and the mechanisms associated with them are the same, only one has been detailed (see Figs. 2, 4, 7 and 9-12).

On each square shaft 51 is a laterally sliding transit carriage 55 to which is pivoted (at 57) a subcarriage 71 having an operating handle 59. Handle 59 has a finger plate 61 bent forwardly and extending through the transit slot 7. Lateral ears 72 serve to pivot 71 at 57 and springs 63 serve normally to hold the arm 59 against the carriage 55.

By grasping the finger plate 61, the carriage 55 may be slidingly moved laterally in transit between various positions under the respective magazines 31. Whenever, but only when, it is over a selector slot 9, the finger plate 61 may be depressed in a plane perpendicular to the sliding movement, with arm 59 then entering a slot 9. In this event, the springs 63 transmit rotary movement from the handle 59 to the carriage 55, as indicated for example by comparing Figs. 9, 10 and 11. However, the springs 63 allow for relative movement between the handle 59 and the carriage 55, should substantial resistance be set up to the rotary motion of the carriage (see dotted lines in Fig. 12). An adjustable set screw 65 provides means for obtaining the proper and desired relative positions between the handle 59 and the carriage 55. Whenever the carriage 55 rotates, the substantially square shaft upon which it is mounted also rotates. The sliding connection between the carriage 55 and the shaft 51 is provided with a quadrilateral (lozenge shaped) opening 67, the shape of which is slightly different from that of the shaft, so that upper and lower point bearings may be obtained at 69, thus assur-

ing easy sliding transit without binding and also rotary movements without too much play.

As indicated in Fig. 7, each carriage 55 has a bottom 73 with up-turned arms 75 at the ends. 5 It is through the arms 75 that the lozenge openings 67 are made and through which the shaft 51 passes.

At each end of each square shaft 51 is supported a sector-shaped ratchet 71 which 10 operates with a corresponding spring-centered pawl 79 (pivoted on the respective side plate 27) to insure that when rotation of the respective shaft 51 has been substantially started in either direction it will be carried to completion before a return action is effected. The pawls 79 are normally held to the central position by means of springs 81. Further description of ratchets and pawls are unnecessary, inasmuch as they are known in the prior art. They are best shown in Figs. 4 and 5.

Each sector 71 on the left side of the machine (Fig. 6) is provided with a roller 83 which extends out through a slot 85 in the corresponding side plates 27 and into the plane of two interlocking bars 87. The bars 87 also have 25 slots 91 accommodating the ends 53 of the upper square shafts 51, said ends 53 of the shafts forming limiting stops against both downward and upward motions of the bars. The ends of the bars are so related to the slots 85 that the swinging of only one roller 83 is accommodated at one time. That is, if one roller is in any of its forwardly drawn positions (to the right in Fig. 6), then neither of the others can move 30 forward. For example if in Fig. 6 the upper roller 83 is moved forward, then the lower rollers 83 are blocked against motion by the lower ends of both bars 87. On the other hand, if the central roller is pulled forward, it will move in 35 between the adjacent ends of the bars 87 and will block the motion of the upper and lower rollers. If the lower roller is moved, both bars will be pushed up to block the motion of the upper and middle rollers. Thus an interlock 40 is obtained between tiers, so that only one of the shafts 51 can be rotated by means of its respective carriage 55. Chamfers 80 facilitate the action.

In addition to the exclusive selective rotary 50 operation as between the three carriages of the respective tiers A, B and C (made possible by the described vertical interlock 83, 87), each carriage may be moved along its respective shaft 51 to dispense selectively from one, but only one, or another of the four magazines in the tier.

Completion of the description of the construction and operation of each carriage and magazine will now be given (Figs. 4, 7 and 9-13). The back 37 of each magazine has a supporting ledge 93 in which are notches 95 providing for the entry from the rear of pusher members 97 when the latter have been moved in transit into proper registry position with respect to the notches (Fig. 13). The pusher members 97 are carried by a frame 99 which has two forwardly extending arms 101 spaced farther apart than the interior width of one magazine 31. These arms 101 extend to a pivot pin 103 which is carried in the upstanding arms 75 of the carriage 55 (Fig. 7). Spacing pillars 106 are used 60 to maintain proper lateral spacing between the arms 101 of the frame 99 and the arms 75 of the carriage 55. The reason for the increased width of the space between arms 101 is so that they will provide an open space at least as wide 65

as the magazine to permit articles (booklets for example) to drop from the bottom of the magazine and through the frame 99 as will appear.

The rear end of each frame 99 carries openings 125 for both pivotal movement and sliding transit movement upon a bar 127. The bar 127 reaches between the supporting plates 27 and extends through bearing openings 129 (see also Fig. 6) for forward and backward movement. Suitable loose exterior washers 131 held by cotter pins 133 serve to guide the rod 127 in successively parallel positions when the frame 99 moves forward. At the same time, the frame 99 may assume any lateral transit position with respect to the rod 127 to accommodate itself to transit positions of the frame 55 on shaft 51.

The front of each magazine has its bottom formed by extensions 102 from the respective shelf 29, these extensions providing notches 105 (Fig. 3). Thus, as shown in Fig. 10, the extensions 102 (at the front) and the extensions 93 (at the back) support the front and back ends of the articles (booklets) 107 which are being vended. The articles or booklets are of rectangular form.

At numeral 4 is indicated a follower weight which rests upon the topmost of each stack of booklets 107. This weight has a handle 6 struck up from its upper surface and recesses 8 which register with the recesses 105 in the shaft 29. These recesses 8 are necessary so that the follower weight does not function as a booklet to become itself ejected after exhaustion of a magazine.

At the front support 102 there is an outlet 109 in each magazine beside which is fastened an adjustable lip 111 with downwardly extending prongs 113 passing into openings of those extensions 102 which are central with respect to the magazines 31. The open portion 115 under each lip 111 serves to accommodate limited motion of the forward end of a lower booklet 107 (Fig. 11), but the downward extension 113 also acts as a limiting stop to further forward movement. The downward extensions 113 also function as loose pivots through openings 117 in the indicators 13 (Fig. 14). The indicators have a bottom ridge portion 119 which pivots at the region of the openings 117. Each indicator 13 also has faces 121 and 123, the former indicating "full" and the latter indicating "empty" when before its respective opening 11. The "full" face 121 is moved into position when the rear portion 120 of the bent plate 119 is depressed, as when the respective magazine is loaded, as indicated in Figs. 9-11.

The extension 120 of the indicator 13 lies between the forward end 157 of the lowermost of articles 107 and the central extension 102 and permits riding forward of the article as desired. The thickness of the extension 120 slightly arches the forward edge of the booklet, but this is provided for in the vertical adjustment of the stop 111. This adjustment also accommodates various thicknesses of booklets which are being dispensed. When the respective magazine is unloaded, as indicated in Fig. 12, gravity causes the front portion of the indicator 13 to drop to present the "empty" face 123 opposite the opening 11. At this time the weight 4 is down but its tongue 122 (between openings 8) does not contact the extension 120 because of notch 124 in extension 120. Thus the indicator is not set by the weight to indicate "full" at this time.

Each carriage 55 supports upon the central

portion of the pivot pin 103 a rotary ejector pawl 135 which has ears or flaps 137 adapted by suitable positioning of the carriage 55 to become aligned with the front openings 105. This is indicated in Fig. 3. The pawl 135 is supported upon the pivot pin 103 by means of ears 139, and is normally spring pressed upward in a counterclockwise position (as viewed in Figs. 9-12), by means of a spring 141. A limiting stop 143 on the carriage 55 (contacted by an extension 144) serves to hold the pawl 135 in clearing position for transit with respect to the under side of the stack of booklets 107 in the magazine when the parts are in the position shown in Fig. 9, that is, with the finger piece 61 up. This permits free lateral movement of the carriage 55 on the square shaft 51, as well as of the attached frame 99 which is moved in transit on the rod 127.

20 The ejector pawl plate 135 includes a lower finger 145 which cooperates with a finger 147 of a dog 149 which is rotary on a pin 151 in the carriage 55. The upward position of the dog 149 is determined by a stop 152 (Fig. 9) when the spring 141 pushes the ejector pawl 135 counterclockwise. When the ejector pawl 135 is rotated clockwise (by means to be made clear), the finger 145 lifts away from finger 147, permitting gravity to rotate the dog 149 from the position shown in Fig. 9 to the position shown in Fig. 10. When the dog 149 is up, as shown in Fig. 9, it interferes with a lip 153 upon any attempt to substantially rotate the carriage 55 (see Fig. 12). Otherwise, the dog 149 clears the lip 153 and permits rotation (see Fig. 10).

35 Operation of the ejector mechanism per se is as follows, referring to a single tier, such as A:

Assuming that the coin release mechanism to be described has been supplied with a suitable 40 coin, the respective finger piece 61 is moved laterally in the transit slots 7 to a position under the magazine having the desired booklet. Piece 61 is then depressed so that its handle 59 passes into the corresponding selector groove 9. Before depression, the position of parts is as shown in Fig. 9. The ejector pawl 135 lies with its lug 144 against the stop 143 on carriage 55. In coming to this position the pawl ends 137 laterally clear the bottommost of the booklets 107 as well as the inner ends of the extensions 102.

50 As the finger piece 61 is depressed (after transit to a slot 9), the carriage 55 receives rotary motion through the spring 63 and rotates the shaft 51, as indicated in Fig. 10. This causes the rear pushers 97 to enter the openings 95 and contact the rear edge 155 of the lowermost booklet 107. At the same time, the rotation of the carriage 55 carries the ejector lug 135 upwardly, so that its tabs 137 are depressed by the lowermost booklet as the lug rotates clockwise relative to the carriage 55 (the latter moving counterclockwise). This action is also shown in Fig. 10. Since the lug 135 rotates clockwise, its finger 145 relieves the finger 147 of the dog 149 so that the latter 55 clears the lip or stop 153, and consequently the carriage 55 may be rotated further. In other words, further substantial action is not blocked.

60 It may here be stated that, if further action is blocked, the carriage 55 returns to its initial position such as shown in Fig. 9, as does also the bed 89 without ejecting a booklet. The spring for this return action is connected with the coin control linkage, and will be described herein-after.

65 Assuming further movement from the position

shown in Fig. 10, the front edge 157 of the lowermost booklet is pushed out of the opening 115 and against the stop 113 as indicated in Fig. 11. The flaps 137 slip off the end of the booklet and swing through openings 105. During this movement, cams 159 on the side bars 101 of the frame 99 contact an edge 161 of a rotary supporting plate 163 which reaches entirely across the machine under the respective tier. This causes the plate 163 to lift into supporting position for the rear portion of the booklet as the rear edge 155 of the booklet drops from the supports 93 (Fig. 11). Thus the final action, as indicated in Fig. 11, is for the ejector pawl 135 to rotate further clockwise (relative to the carriage 55), so as to spring from under the front end 157 of the booklet as shown in Fig. 11. The dog 149 at this time is resiliently held against its stop 152 and upon subsequent upward movement can spring past ledge 153.

Finally, the customer, having reached the end of the down-stroke of the finger plate 61, releases it, whereupon the shaft 51 returns clockwise (by spring means to be described) to return the carriage 55 clockwise. This causes the fingers 137 of the ejector pawl 135 to contact the front edge 157 of the lowermost booklet 167 to push it backward, as indicated by comparing Figs. 11 and 9 successively. During this action, the lower end of the dog 149 drags over the lip 153 and snaps into position above it, the spring 141 permitting this action. The booklet as it is pushed backward is pushed over the edge of the plate 163 and is thus directed between the deflector plates 43 and the back 45 to slide out over the curved deflector 47 and out of the opening 15. As the frame 99 returns to the rear, the next highest but bottommost booklet drops into position for a repetition of the action. Each time that the frame 99 moves forward, the supporting shaft 127 moves into returned position in the slots 129.

After a magazine has been exhausted, as indicated in Fig. 12, not only does the indicator plate 119 move into a position to show empty, because of the absence of weight on extension 120, but it is impossible to make another full stroke ejecting action, because under such conditions there is no bottommost booklet to turn the ejector lug 135 clockwise relative to the incipient counterclockwise action of the carriage 55. This means that the dog 149 will never drop clear from the ledge 153. This prevents further substantial motion of the carriage 55. This prevents the mechanism from proceeding to a position wherein the pawls 79 catch in the ratchets 77 and prevent a coin (which the customer has heretofore deposited) from being discharged into the money box of the apparatus, as will be shown. Thus the coin is left in a position wherein operation of the coin-return lever 21 may retrieve it.

It is important to state here the fact that when the counterclockwise action of the carriage 55 is blocked, as above made clear, the customer may inadvertently apply extra force to the finger plate 61 in an attempt to obtain a delivery of an article. This will not have the effect of abusing the mechanism, because it will simply cause deflection of the spring 63 to an extent wherein angling occurs between the lever 59 and the carriage 55, as indicated in Fig. 12.

Although the above operation is described in connection with the top level of the machine at tier A, a similar operation occurs on each of

the levels B and C, by means of the respective carriages in connection therewith. However, in the case of the lowermost level, a supporting bar such as 163 is not used. As the rear edge 5 of the bottommost booklet 167 moves forward and then drops down it is supported upon the edge portion 165 of the deflector plate 49, and then upon the rearward ejection stroke, the front edge falls down and the booklet slides 10 directly out of the opening 15. The purpose of the automatic supporting devices 163 in connection with the upper tiers is to cause the booklet to move to the back of the cabinet in falling so that it does not become entangled in the apparatus in the lower tiers.

The coin controlled mechanism will now be described. This is located on the right-hand side of the machine (Figs. 4 and 5) and comprises a drag link 167 which is normally held in an upward returned position by a spring 168 (Fig. 4). Pivoted to the drag link 167, for use at each of tiers A, B and C are bell-cranks 169. The bell-crank in connection with the upper tier A is not shown in Fig. 4 because of the fact that parts 20 are broken away, but it is the same as the one shown in connection with tier B. Each bell-crank 169 is pivoted at 171 to the right-hand side plate 27, and has a downwardly extending arm 173 with which cooperates a roller 175. 25 Each roller reaches through a slot in the right-hand side plate 27. The rollers 175 reach from the right-hand set of ratchets 77 on square shafts 51. Thus it will be seen that any time that one of the square shafts 51 is rotated by 30 means of its lever 59 it rotates its respective bell-crank 169 and all of the other bell-cranks 169 are likewise rotated by reason of the drag link connection 167. This however does not involve rotation of the other square shafts 51, because, although the rollers 175 push the levers 173, the reverse action does not necessarily occur.

The purpose of the drag link connection is to insure operation of the lowermost bell-crank 169 when any other one is operated by action 45 of its respective square shaft 51. The lowermost bell-crank 169 carries a sector extension 177 (shown also in Fig. 8) behind which is received (from a coin passage 179) the controlling coin 199. This type of coin release mechanism is generally known and comprises a spur 181 which, if a coin is not in position, upon incipient motion of the sector member 177 comes into contact with a pawl 183 which is normally pulled into a downward position by a spring 185. Thus without a 50 coin, any action of the device is blocked by cooperation between the spur 181 and the pawls 183.

On the other hand, when a coin 199 is in position, as shown in Fig. 5, it acts as a cam over 55 the spur 181 to lift the pawl 183 so that the pawl clears the spur 181. This permits full stroke action of the device and movement of the coin 199 from a seat 191 and into the channel 187 (Fig. 5) and coin box 189.

Prior to dropping of the coin into the chute 60 187 it is supported upon said support 191 and is pushed into the chute 187 by the action of a backing pin 193. The addition of this pin or its equivalent, and the provision for its release, is new in the present device. It is shown in Figs. 4, 5 and 8. For supporting the pin, a horizontal platform 195 is attached to the sector extension 177. Ears 197 thereon slidably support the pin 193 for lateral movement into position behind the coin 199. A spring 201 normally pushes a lug 70 203 of the pin 193 to force the pin into the posi-

tion shown in Fig. 8, which is the position behind the coin 199, for moving the coin over into the slot 187 when the sector 177 operates.

To pull the pin 193 out from the coin 199 a bell-crank 205 is provided on a pin 207 which in turn is supported upon the horizontal plate 195. One arm of the bell-crank 205 operates behind the lug 203 to withdraw the pin and the other arm is contacted by the depending arm 209 of another bell-crank 211 in a 90° plane. The other arm 21 of the bell-crank 211 extends out through the slot 19 (Figs. 1, 4 and 5) and has already been mentioned as being the coin return arm. Whenever a customer desires return of a coin, either before an attempted operation, or after an attempted or unconsummated operation, he simply presses upon the coin return lever 21, whereupon the bell-crank 211 rotates counterclockwise thus rotating the bell-crank 205 counterclockwise (Fig. 8) and withdrawing the pin 193 from behind the coin 199. Since the support 191 for the coin slopes slightly to the left, the coin will then roll out over the guide 213 and into a return chute 215, at the bottom of which is an outlet 217 into the opening 15.

The overall operation from the customer's viewpoint will now be described. He drops the requisite coin (for example a dime) into the slot 17. The slot 17 passes through a coin selector mechanism 218 as indicated in Figs. 4 and 5. If the coin is bad, it sticks at shelf 216 and can be cleared only by depressing shelf 216 to fall through passage 219 to be returned at 25. This coin selector mechanism 218 per se forms no part of the present invention and other forms may be used if desired. Further description is not necessary except to state that downward release at 216 is effected by a connection 220 with lever 21, as indicated at 222. The selector mechanism has not been described in detail, because it is an attachment of one character or another for separating good and bad coins and per se forms no part of the present invention.

It suffices to say that it selects good coins from bad to be delivered into the passage 179 via the good-coin route 224. Bad coins never enter passage 224 or 179 and are delivered into a passage 219 which delivers them into the return chute 23 as described.

Assuming the coin to be a good one, it traverses paths 224, 179 and drops into position on the support 191 behind the sector plate 177 as indicated in Figs. 5 and 8. It is held from gravitating to the left by pin 193. This makes the machine potentially operable from any one of the finger plates 61 in any one of the tiers A, B or C.

One of the finger plates 61 is then moved along its transit groove 7 to the desired panel 5 and depressed into the desired selector groove 9. If the corresponding magazine is full, the bottommost booklet is ejected by means of the forward and backward strokes of frame 99, upon depressing and releasing the respective finger plates, as above described. The depressing action will rotate the corresponding carriage 55 and shaft 51 and also the respective endwise bell-crank 169 (Fig. 4). This, through the drag link 167, operates the lowermost bell-crank 169 with its coin control extension 171. All action can hence proceed when the coin is in position, and consequently a booklet is delivered and the coin is delivered to the coin box 189 through the passage 187.

At any time before pressing down the desired

finger plate 61, the customer may change his mind as to the panel from which he wishes to withdraw a booklet. It is expected that he will normally try to withdraw booklets from full panels, but if he inadvertently should place the selector 61 under an empty panel and press it down, rotary action by the carriage 55 would be blocked as indicated in Fig. 12 and above described, before the mechanism would be driven into a position such as to send the coin through chutes 169 and 187 to the coin box 189. Although the customer may then violently push down the finger plate 61, no damage can be done to the mechanism in its position under the respective empty magazine (see springs 63; Fig. 12).

From this point on, the customer may either decide to take a booklet from another full magazine, in which event he simply shifts the position of the carriage by putting the finger plate 61 under another magazine; or he may decide that he does not want a booklet at all, in which event he simply depresses the coin return lever 21 and obtains a return of the coin from the chute 215 at point 25.

On the other hand, once the customer substantially depresses the finger plate 61 beneath a full magazine, he cannot do anything but complete the action. No return action is possible without a delivery of a magazine because of the full stroke ratchets 77 and the cooperating pawls 79. This is to prevent tampering in order to obtain a booklet and the return of its cost at the same time.

This invention has various advantages over that disclosed in my said former application and the prior art in general. In the present case, only three manipulating points (finger plates 61) are used; whereas in my former case, one manipulating rod was used in connection with each magazine.

The present invention, while using vertical interlocks between tiers, avoids the necessity for cross interlocks for magazines in a tier. This is because of the selective transit action of the single travelling carriage under the magazines of a given tier.

The short and partial forward delivery stroke and the short, doubling, rearward, ejecting stroke for causing movement of a booklet from its magazine to delivery position results in the machine being quite shallow, considering the length of article being dispensed. Along with this is the ease with which provision may be made for interlocking against operation when a magazine is empty.

Another advantage is that, in the case where a magazine is empty or in the case where a customer changes his mind before operation is initiated under any magazine, the customer may obtain the return of the purchase price before delivery of a booklet. That is to say, carriage operation is blocked and no motion is delivered to the coin operated mechanism when no booklets are present in a magazine, and this feature is so arranged (in connection with provision for return of the coin upon mere decision of the customer) that many parts are saved.

Another advantage is the simple "full-empty" signal means.

Another advantage is in the safety spring mechanism between the operating finger pieces and the carriages to prevent breakage when rotary motion of the carriage is blocked, as when a magazine is empty and a customer uses undue force.

It is clear that as many magazines may be used

in a tier as desired, and also any desirable number of tiers may be used. Various articles may be accommodated at various prices without change in principle.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A vending machine comprising a magazine, said magazine having an open bottom with front and rear article supporting shelves and having an outlet at the front shelf permitting limited forward movement of an article so as to release its rear portion from the rear supporting shelf, a reciprocating frame movable forward to push a lowermost article from said rear shelf, whereby it is held on the front shelf, and pawl means at the front portion of the frame responsive upon contact with the front portion of the lowermost article to move into position for ejecting the article from the front shelf upon return movement.

2. A vending machine comprising a magazine, said magazine having an open bottom with front and rear article supporting shelves and having an outlet at the front shelf permitting limited forward movement of an article so as to release its rear portion from the rear supporting shelf, a reciprocating frame movable forward to push a lowermost article from said rear shelf, whereby it is held on the front shelf, and pawl means at the front portion of the frame to eject the article from the front shelf upon return movement.

3. A vending machine comprising a magazine, said magazine having an open bottom with front and rear article supporting shelves and having an outlet at the front shelf permitting limited forward movement of an article so as to release its rear portion from the rear supporting shelf, a reciprocating frame movable forward to push a lowermost article from said rear shelf, whereby it is held on the front shelf, pawl means at the front portion of the frame for ejecting the article from the front shelf upon return movement of the frame, and means responsive to the initial movement of said pawl permitting reciprocation of the frame only when the pawl responds to contact with an article within the magazine.

4. A vending machine comprising a magazine, said magazine having an open bottom with front and rear article supporting shelves, and having an outlet at the front shelf permitting limited forward movement of an article so as gravitationally to release its rear portion from the rear supporting shelf, a reciprocating frame movable forwardly to push a lowermost article from said rear shelf only, pawl means at the front portion of the frame contacting with the front portion of the lowermost article for ejecting the article from the front shelf upon return movement of the frame, means responsive to the initial movement of said pawl permitting substantial reciprocation of the frame only when the pawl initially responds to contact with an article within the magazine, said frame being adapted to permit passage of ejected articles therethrough.

5. A vending machine comprising a magazine, said magazine having an open bottom with front and rear article supporting shelves, and having

an outlet at the front shelf permitting limited forward movement of an article so as gravitationally to release its rear portion from the rear supporting shelf, a reciprocating frame movable

5 forwardly to push a lowermost article from said rear shelf only, pawl means at the front portion of the frame contacting with the front portion of the lowermost article for ejecting the article from the front shelf upon return movement of the frame, means responsive to the initial movement of said pawl permitting substantial reciprocation of the frame only when the pawl initially responds to contact with an article within the magazine, said frame being adapted to permit passage of ejected articles therethrough, a movable support transverse of the frame and a cam on the frame adapted upon forward movement to move said support into temporary supporting position for an article which is free of the rear shelf but on the front shelf.

6. A vending machine comprising a magazine, said magazine having an open bottom with front and rear article supporting shelves and having an outlet at the front shelf permitting limited forward movement of an article so as to release its rear portion from the rear supporting shelf, a reciprocating frame movable forward to push a lowermost article from said rear shelf, whereby the article is held on the front shelf, pawl means at the front portion of the frame responsive upon initial contact with the front portion of the lowermost article to move subsequently into position for ejecting the article from the front shelf upon return movement of the frame, a stop, a dog organized for movement with said frame and engaged by the pawl and additionally movable by the pawl when the pawl contacts said lowermost article, whereby the dog clears the stop, said dog engaging said stop to lock against complete movement of the frame when said pawl fails to move in the absence of any article in the magazine.

7. A vending machine comprising a magazine, said magazine having an open bottom with front and rear article supporting shelves and having an outlet at the front shelf permitting limited forward movement of an article so as to release its rear portion from the rear supporting shelf, a reciprocating frame movable forward to push a lowermost article from said rear shelf, whereby the article is held on the front shelf, pawl means at the front portion for ejecting the article from the front shelf upon return movement of the frame, and means responsive to the initial movement of said pawl permitting substantial reciprocation of the frame only when the pawl responds to contact with an article within the magazine, whereby substantial operation is prevented under empty condition of the magazine, and a follower for the column of articles having clearing space to prevent cooperation with the said pawl, so that the follower does not function as an article to be finally ejected.

8. A vending machine comprising a magazine for a column of articles to be dispensed, said magazine having a forward opening permitting limited forward movement of said articles, said magazine being open at the bottom and having forward and rearward supporting shelves for the column of articles, supporting means for transverse movement of an ejector mechanism into position, a rotary carriage, a frame pivoted at the front to the carriage and mounted at the rear for reciprocation by the carriage, lug means on the rear of the frame for contacting a lowermost ar-

title to push it a limited distance and from the rearward shelf upon rotation of the carriage, a stop transverse of the carriage, a dog on the carriage normally cooperable with said stop, a movable ejecting pawl adapted upon one movement of the carriage to contact the front of an article to effect movement of the dog to positions whereby carriage movement may continue, but permitting positioning of the dog to block carriage movement when no article is in the magazine, said pawl functioning as an ejector upon reverse rotation of the carriage and return movement of said frame.

9. A vending machine comprising a magazine for a column of articles to be dispensed, said magazine having a forward opening permitting limited forward movement of said articles, said magazine being open at the bottom and having forward and rearward supporting shelves for the column of articles, supporting means for transverse movement of an ejector mechanism into position beneath said magazine, said ejector mechanism comprising a rotary carriage, a frame pivoted at the front to the carriage and mounted at the rear for reciprocation by the carriage, lug means on the rear of the frame for contacting a lowermost article to push it a limited distance and from the rearward shelf upon rotation of the carriage, a stop transverse of the carriage, a dog on the carriage normally cooperable with said stop, a movable ejecting pawl adapted upon one movement of the carriage to contact the front of an article to effect movement of the dog to positions whereby carriage movement may continue, but permitting positioning of the dog to block carriage movement when no article is in the magazine, said pawl functioning as an ejector upon reverse rotation of the carriage and return movement of said frame, whereby said lowermost article is removed from the forward shelf, said frame having an opening surrounding the lower end of the magazine to permit falling therethrough of said article after removal.

10. A vending machine comprising tiers of article-supporting magazines, a movable lateral guide means associated with each tier, an ejecting means movable along each guide means into position adjacent to any magazine in the associated tier, the ejecting means being organized with the respective guide means to move the guide means when the ejecting means are given additional ejecting movements, means determining that each ejecting means may receive an ejecting movement only when in a predetermined position adjacent to a magazine in its respective tier, and interlocking means between the respective guide means, whereby only one guide is movable at a time and therefore only one ejecting means is operable at a time to eject from one magazine in its respective tier.

11. A vending machine comprising tiers of article-supporting magazines, a movable lateral guide means associated with each tier, an eject-

ing means sliding along each guide respectively into position under any magazine in the associated tier, the ejecting means being organized with the respective guide means to rotate the guide means when the ejecting means are given additional rotary ejecting movements, means determining that each ejecting means may receive an ejecting movement only when under a magazine in its respective tier, each ejecting means freely sliding on its respective guide means independently of movement of the other ejecting means, and interlocking means between the respective guide means, whereby only one guide is movable at a time and therefore only one ejecting means at a time is rotary and operable to eject from one magazine.

12. A vending machine comprising tiers of article-supporting magazines, a movable lateral guide means associated with each tier, ejecting means sliding along each guide means into position adjacent to any magazine, the ejecting means being organized with the respective guide means to move the guide means when the ejecting means are given additional ejecting movements in planes perpendicular to the sliding movements, means determining that each ejecting means may receive an ejecting movement only when predeterminedly positioned with respect to a magazine in its respective tier, and interlocking means connected between the respective guide means, whereby only one guide means is movable at a time and therefore only one ejecting means is operable at a time to eject from one magazine.

13. A vending machine comprising horizontal tiers of magazines for columns of articles to be dispensed, transit means movable to selected positions beneath the said magazines including means operable in said transit means in a selected position for removing the bottommost article of a column in a respective magazine, and locking means for preventing any substantial ejecting operating movements in said transit means in a selected position when the respective magazine is empty.

14. A vending machine comprising horizontal tiers of magazines for columns of articles to be dispensed, transit means movable to selected positions beneath the said magazines including means operable in said transit means in a selected position for removing the bottommost article of a column in a respective magazine, locking means for preventing any substantial ejecting operating movements in said transit means in a selected position when the respective magazine is empty, a manually operable member movable with the transit means for effecting operation, and resilient means connecting the member and transit means providing for manual operation of said member without operation of the article-removing means when the latter is locked.

BENJAMIN W. FRY.
